UNITED STATES PATENT OFFICE.

ALLAN A. ADAMSON, OF ROCHESTER, NEW YORK, ASSIGNEE TO GEORGE H. HARRIS, OF ROCHESTER, NEW YORK.

MANUFACTURE OF CIGAR BOXES AND THE LIKE.

Application filed January 31, 1925. Serial No. 5,920.

The present invention relates to the manufacture of cigar boxes and the like, and more particularly to the type where the box is made of wood, paper board, or a combination of the two and provided with edging which covers the vertical corners, horizontal bottom corners, and also the upper edges of the vertical wall and edges of the cover. An object of this invention is to provide for 10 economically applying the edging to the boxes. Another object of the invention is to combine the edging with labels so as to dispense with a separate application of the labels. Still another object of the invention 15 is to provide for applying to the cover or lid of the box a combined edging and label formed from a single piece of material.

To these and other ends, the invention consists of certain parts and combinations 20 of parts, all of which will be hereinafter set forth; the novel features being pointed out in the appended claims.

In the drawings:

Fig. 1 is a perspective front view of a box 25 constructed in accordance with this invention with a part of the lid or cover being broken away;

Fig. 2 is a perspective rear view of a box 30 constructed in accordance with this invention with part of the lid or cover being broken away;

Fig. 3 is a plan view of an edging blank for the front wall of the body;

Fig. 4 is a plan view of the edging blank 35 for the rear wall of the body;

Fig. 5 is a plan view of one of the combined label and edging blanks for the two end walls of the body;

Fig. 6 is a plan view of the combined 40 label and edging blank for the lid or cover;

Fig. 7 is a top view of the cover with the combined labeling and edging blank applied thereto; and

Fig. 8 is a rear view of the box before 45 the rear section is applied.

In the manufacture of cigar boxes it has been the custom for years to trim the corners or edges of the box with edging formed from separate pieces of material, to apply 50 these pieces separately by hand, and then to apply the labels to the box over this edging. This method of edging a box and the application of labels thereto has necessitated a large number of operations which have 55 added materially to the cost of manufac-

ting cigar boxes. Furthermore, this method has prevented the edging and labeling of the boxes by automatic machines.

According to this invention the edging is so formed that the number of operations required in applying the same is reduced to a minimum. At the same time labels are combined with edging and the whole is formed so that the edging and labeling may be handled by automatic machinery. In the illustrated embodiment of the invention the edging and labeling for the box and its cover or lid are formed by five sections or pieces.

The front edging section piece illustrated in Fig. 3 is in the form of a blank 1 with a central opening 2. This blank has at its lower edge a portion 3 foldable on a line 4 to provide with the lower portion of the blank the edging for the lower front corner. The blank also has a portion 5 foldable on the lines 6 and 7 to provide with the adjacent portion of the blank the edging for the upper front edge of the box. This portion 5 is shorter than the portions 3 and lies between the two lips or extensions 8 on the blank 1. These extensions or lips are utilized to cover those portions of the end walls 9 of the box which project above the front and rear walls 10 and 11, respectively. For covering the rear wall of the box a blank 13 is provided which has a portion 14 foldable on a line 15 to extend over the rear portion of the bottom of the box. This blank at its top edge has a shorter tongue 16 foldable on the lines 17 at the hinge of the box and on the line 18 at the rear corner of the cover of the box the tongue overlying the rear top surface of the cover on opposite sides of this tongue 16 tongues or extensions 19 are provided to cover those portions of the end walls projecting above the rear wall.

The end sections 23 illustrated in Fig. 5 of which there are two, each has a lower portion 24 foldable on a line 25 to extend over the bottom of the box, the sections 23 also each having a portion 26 foldable on lines 27 and 28 to cover the upper edges of the box, the portion 26 having shoulders 29 at opposite ends beyond the folds 27 so that those portions of the end walls above the front and rear walls of the box may be covered on their inner sides by the portions 30 between the shoulders 29 and the fold 27. Tongues 13^a may be provided at opposite ends of the blanks foldable on the lines 13^b 110

to overlap the front and rear walls. The blank 23 preferably is not cut away, but is solid so that any suitable advertisement as at 31 may be printed thereon for advertising the cigars.

The lid or cover 32 may be labeled and edged by the blank on its inner face and edged by the blank 33 shown in Fig. 6. This blank has portions 34 on three sides foldable on the lines 35 and 36 so as to extend over the edges of the lid or cover and onto the top face thereof. At its other edge, the blank 33 has a wide lip or label extension 37 for providing a label on the inner face of the rear wall of the box.

In labeling and edging the box the end sections 2 are first applied. Thereafter, the front section 1 is applied. This provides edging for the front and end walls. The cover or lid being a separate piece has the section 33 applied thereto so that before it is applied to the box body, it has the appearance shown in Fig. 6. The lid or cover is then secured to the rear wall of the box by a strip 38 of cloth or similar material such as is commercially used, the parts after the application of the hinge having an appearance such as shown in Fig. 8. After the hinge is set the section 13 is applied to provide edging for the rear wall and the rear portion of the cover.

This invention reduces the number of operations required in edging cigar boxes and the applying of labels thereto. The label and edging for the cover or lid are formed in one piece, except for the rear edge of the cover or lid. The edgings for the four vertical walls are formed in four separate pieces with portions provided for extending about the top edges of such walls and onto the bottom. This construction makes it possible to adhesively secure the hinging strip directly to the material of the box body and the

cover, these parts being exposed at a desirable time for connecting with the hinging strip to the cover and the box body.

What I claim as my invention and desire to secure by Letters Patent is:

1. In combination with a cigar box lid, a combined label and edging blank having a main portion covering the inner face of the lid and provided with tongues on three sides, extending around three edges of the lid and onto the top surface thereof, the hinging edge of the box or lid being exposed for the attachment of a hinging piece.

2. In combination with a cigar box lid, a combined label and edging blank having a main portion covering the inner face of the lid and provided with tongues on three sides, extending around three edges of the lid and onto the top surface thereof, the hinging edge of the box or lid being exposed for the attachment of a hinging piece, and a label extension on the bottom portion of the blank for attachment to the inner face of the rear wall of a box.

3. The combination with a box body and a lid hinged thereto, of a combined labeling and edging blank having a main portion secured to the inner face of the lid, edging portions extending from said main portion around the edges of three sides of the lid and onto the rear side of the lid, and a label extension extending from the main portion downwardly and secured to the inner face of the rear wall of the box body.

4. In combination with a cigar box having a hinged cover, of an edging blank for edging the rear wall of the box having tongue portions edging the rear top face of the cover adjacent the hinge and the rear bottom face of the bottom of the box and separate edging means for the other three edges of the cover.

ALLAN A. ADAMSON.
